UNITED STATES PATENT OFFICE

ESTHER GERTSFELD, OF NEW YORK, N. Y.

NECKTIE

Application filed June 24, 1931. Serial No. 546,493.

This invention relates to an improvement in neckties. It has for its object to provide a necktie of such construction as will enable the same to be maintained in the proper 5 shape, consequently giving long wear and at all times presenting a smooth and unwrinkled appearance. I obtain this object by the utilization of means whereby either the tie body or the tying ends thereof may 10 be readily opened and spread out flat to permit the tie to be easily cleaned and pressed, or in the case of washable ties, to permit the same to be laundered and thereafter pressed and refolded to restore it to its former condition, whereupon the tie will present the 15 aspect of an unwrinkled or new tie. The primary object therefore, of this invention, is to provide a tie which can be kept in such condition as to maintain a smooth and unwrinkled condition for its entire life, due to 20 the fact that the tie may be easily pressed and renovated to maintain its appearance.

Reference is to be had to the accompanying drawings forming a part hereof, in which 25

Figure 1 is a view of the rear face of a necktie made in accordance with my invention;

Figure 2 is a similar view of the tie showing the necktie body opened up and spread out flat to place the tie in condition for pressing;

Figure 3 is a view of a part of the necktie body showing one of the folds thereof drawn away to disclose the lining and interlining, a part of the lining being broken away to 35 show the interlining;

Figure 4 is a sectional view on the line 4—4 of Figure 1, looking in the direction of the arrows;

Figure 5 is a view of the back face of a 40 modified form of necktie;

Figure 6 is a view of the lower part of the large end of another form of necktie with one of the folds thereof being drawn back to 45 disclose the lining;

Figure 7 is a portion of another form of necktie;

Figure 8 is a sectional view on the line 8—8 of Figure 6, looking in the direction of the 50 arrows, and

Figure 9 is a view of a part of the necktie shown in Figure 5.

In the embodiment of my invention disclosed in Figures 1 to 4 inclusive, 9 indicates the necktie body, which is preferably composed of silk, or some similar textile fabric, the threads thereof being preferably located on the bias with respect to the body of the tie whereby said necktie body has a considerable degree of longitudinal elasticity. The 60 necktie body thus constructed is provided with the conventional narrow neck band 15, smaller tying end 13 and larger tying end 14. The folds of the tie are overlapped at the rear face thereof in the usual manner and 65 said folds are detachably connected together for the entire length of the tie by means of flexible fabric loops 17 secured along one of the longitudinal edges of the tie body, which loops engage with buttons 16 provided on the outer face of the other necktie fold. In the construction of the tie disclosed in Figures 70 1 to 4 inclusive, I have shown said tie as being provided with an outer necktie body 10 of bias fabric as heretofore explained, and a 75 lining 11 which is preferably of a thinner fabric and which is also preferably a bias fabric so that the same is longitudinally extensible co-extensive with the outer covering 10.

Located between the outer covering 10 and lining fabric 11, is the necktie interlining 12 which is so shaped that it defines the resultant outline of the necktie. Said interlining 12 is preferably composed of a woven bias fabric, such as an all-wool fabric having a considerable degree of elasticity. The fabric loops 17 which co-operate with the buttons 16 to hold the necktie together in its folded condition, 80 preferably have their ends anchored between the outer fabric 10 and the lining fabric 11 as disclosed in Figure 3. The necktie in condition for use is disclosed in Figure 1 wherein it will be seen that the loops 17 are engaged with the buttons 16 thus detachably uniting 85 the overlapped folds of the necktie on the back face of the same. The flexibility of the loops 17 is such that the same freely give with the necktie pull and in nowise affect the longitudinal elasticity of the necktie. Such 100

longitudinal elasticity is of a considerable degree since all of the necktie elements, and particularly the outer covering 10, lining 11 and interlining 12 are of bias fabric, affording the desired elasticity just referred to.

5 When the tie becomes wrinkled from use, the loops 17 are disengaged from the buttons 16, whereupon the entire necktie body composed of the several fabric layers, may be spread out flat as shown in Figure 2 and readily cleaned, pressed or ironed. After being ironed, in the flat condition just referred to, the tie is folded back on the fold lines 18a and 19a and the loops engaged with the buttons 16; the tie then presenting a smooth and restored appearance. By the arrangement just described dry cleaning or laundering of the necktie is also facilitated.

10 In the embodiment of my invention disclosed in Figures 1 to 4 inclusive, I have shown the detachable fastening elements, namely, the loops 17 and the buttons 16, extending for the entire length of the tie. It will be readily understood, however, that 15 these fastening elements may, if desired, extend merely through the large and small ends 13 and 14 of the tie, or if found desirable, they may merely extend through the large end of the tie, the remaining parts of the tie being 20 permanently stitched together in the conventional way. Thus, that part of the tie which is subjected to the most wear and which exhibits the greater tendency to wrinkle may be provided with these detachable fastening 25 means to enable that part of the tie to be opened out flat, pressed, and then restored to shape as was heretofore described.

30 In Figure 5 I have shown a necktie body constructed as heretofore described but with 40 a different form of detachable fastening means used for uniting the folds. The fastening means consist of a lengthy piece of heavy thread, cord, tape, thin rubber, or some similar flexible element 21, which is adapted 45 to pass through a series of reinforced holes 18 provided in one of the necktie folds, and also engaging with a similar series of holes 19 provided in the other fold of the necktie body. The holes in one fold of the tie overlie 50 those in the other fold. Thus, the flexible element 21 is passed through said holes and serves to hold the folds of the tie together. The two series of holes 18 and 19 may extend for the entire length of the tie or the same 55 may be omitted in the neck band portion 15 and the portion of the member 21 located within that area may be "slip-stitched" through said neck band if desired. The flexible connection member 21 is provided with 60 free extended ends 22 which are located within the tie body. Said member 21 may be readily withdrawn from the tie so that the tie body can be spread out flat in the manner heretofore described for pressing purposes. 65 This type of tie may, due to the construction

of its fastening means, be reversed and worn with its lining outermost. The tie is made easily reversible by removing the member 21 and replacing it after the tie has been folded with the lining on the outside. The member 70 21 may, after the tie is pressed, be easily threaded back into its former position to detachably unite the necktie folds in the manner disclosed in Figure 5. Said member 21 being loosely threaded through the holes and having free ends, receives none of the pulling strain imposed on the tie. As was heretofore stated, the holes 18 and 19 may be situated merely in the smaller and larger ends of the tie or in either of them, or these holes may 80 extend throughout the full length of the tie.

85 In the modified structure disclosed in Figure 6, an unlined necktie body is disclosed, the same merely having a bias interlining 25. The folds of the necktie body there disclosed are detachably held in their usual overlapped relationship by means of fabric loops 24 located on one of the folds and projecting from the edge thereof, and engaging with buttons 23 located on the face of the other fold. The 90 buttons 23 are secured to the fold to which they are attached as by the stitches 30, which stitches also pass through the interlining 25 as disclosed in Figure 8. In the structure of Figure 6, the entire lining is spread out flat 95 when the fold to which it is attached is also spread flat for ironing or pressing.

100 In Figure 7 a further modification is shown wherein one of the folds of the necktie is provided on its outer face with fabric loops 26 that are engaged by hooks 27 that are stitched to a bias fabric strip 28 and have their inner ends located between said strip and the inner face of the necktie fold to which the strip is secured. These hooks 27 105 detachably engage with the loops 26 and hold the necktie body in its proper position. The hooks 27 are so located that when the folds of the necktie are united said hooks are concealed by the fold to which they are attached, 110 and the connection between the overlapped folds of the tie is similar to that of the ordinary necktie since the fastening means is concealed. The bias tape 28 is extensible 115 with the other necktie elements and in no way restricts the natural elasticity of the tie. In place of the concealed hooks 27 and loops 26 engaged thereby, buttons and button holes may also be provided in the necktie folds, and so arranged that the same are 120 concealed when the folds of the tie are united.

125 These and other modifications may be made without departing from the spirit of my invention.

What I claim is:—

1. A necktie having a body portion provided with folds, said necktie body being composed of an outer fabric, a lining extending over and covering the inner face of the same, an interlining disposed between the outer 130

5 fabric and lining, a group of flexible loops attached to one of the folds, said loops having their ends disposed between the outer fabric and the lining, and buttons on the face of the other fold for engagement by said loops.

2. A necktie having a body portion provided with folds, said necktie body being composed of an outer fabric, a lining consisting of a strip of fabric conforming in shape to 10 the body and overlying and completely covering the inner face of the necktie body, an interlining disposed between the necktie body and lining, said interlining defining the shape of the folded necktie, a group of fastening 15 members attached to one of the folds, the fastening members having their ends held between the outer fabric and the lining and their operative fastening portions projecting from the edge of the fold, and complementary fastening members disposed on the 20 face of the other fold for engagement by the fastening members of the first group.

3. A necktie having a body portion provided with folds, said necktie body being composed of an outer fabric, a bias fabric located on the inside of the necktie body and having an edge extending co-extensive with an edge of the necktie body, a group of fastening members attached to one of the folds, 25 said fastening members having their ends held between the co-extensive edge portions of the bias fabric and the necktie body, and complementary fastening members disposed on the face of the other fold for engagement 30 by the fastening members of the first group.

Signed in the city, county, and State of New York, this 23rd day of June, 1931.

ESTHER GERTSFELD.
